To all whom it concern:

Be it known that we, John L. Haddock and Steve Dixon, citizens of the United States and residing respectively at Compton and Long Beach, in the county of Los Angeles, State of California, have invented a new, original, and ornamental Design for a Sucker Rod Clamp, of which the following is a specification, reference being had to the accompanying drawing, forming part thereof, in which:

Fig. 1 is a perspective view of the sucker rod clamp as seen from the front end and front side thereof showing our new design;

Fig. 2 is a view of the sucker rod clamp as seen in rear elevation;

Fig. 3 is a plan view;

Fig. 4 is a front end view; and

Fig. 5 is a rear end view.

We claim:

The ornamental design for a sucker rod clamp, substantially as shown.

JOHN L. HADDOCK.
STEVE DIXON.
